HOUSING FOR AN ELECTRO-MAGNETIC WAVE DETECTOR OR SIMILAR DEVICE

William L. Waytena, Tonawanda, N.Y., assignor to Rada-tron Research and Development Corporation, Tonawanda, N.Y., a corporation of New York

Filed May 8, 1961, Ser. No. 65,074

Term of patent 14 years

(Cl. D26—5)

FIG. 1.

FIG. 2.

FIG. 3.

FIG. 4.

FIGURE 1 is a perspective view of a housing for an electro-magnetic wave detector or similar device, showing my new design;

FIGURE 2 is a side elevational view, to a reduced scale, the opposite side being substantially a mirror image thereof;

FIGURE 3 is a front elevational view, to a reduced scale; and

FIGURE 4 is a top plan view thereof.

The broken line showing of legible matter in the drawing is for illustrative purposes only.

My design is characterized by the raised dial surface in association with the horizontal grille and the particular rectangular, horizontally disposed leg members, all as shown.

I claim:

The ornamental design for a housing for an electro-magnetic wave detector or similar device, substantially as shown and described.
